UNITED STATES PATENT OFFICE

2,452,030

STEP-UP MECHANISM

Edward H. Hughes, Chicago, Ill., assignor to Exhibit Supply Company, Chicago, Ill., a corporation of Illinois

Application October 4, 1946, Serial No. 701,362

4 Claims. (Cl. 74—142)

1

This invention relates to certain new and useful improvements in step-up mechanisms adapted for use in many arts. The present invention is especially designed and adapted for use in an amusement apparatus wherein a score indicia wheel is stepped up as scoring is achieved and returned to normal or initial position, as when zeroizing the scoring wheel or resetting the apparatus for different or additional play.

The principal and primary object of this invention is to provide in such a mechanism an arrangement for latching the step-up and return latch lever in unlatched relation with respect to each other until a switch is closed at the initial playing of the amusement apparatus, the said switch being usually in the form of a ball bumper switch such as is disclosed in United States Patent No. 2,109,678, dated March 1, 1938. In accomplishing this object, at each initial operation of the step-up wheel, the wheel is at all times in zero position, thereby preventing enlargement of the score which would otherwise result where the wheel starts in its initial movement from a position other than zero position.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention;

Fig. 2 is a fragmentary perspective view of the invention showing certain parts illustrated in Fig. 1 in enlarged position;

Fig. 3 is a fragmentary perspective view similar to that shown in Fig. 1 showing the advancing arm and the latch arm in operative engagement with respect to the step-up wheel; and

Fig. 4 is a fragmentary perspective view similar to Fig. 1 but showing the parts in unlatched position with respect to the step-up wheel.

The several objects of my invention are accomplished by the preferred form of construction as shown in the accompanying drawings.

The usual and conventional step-up mechanism comprises a mounting plate 10, on which there is rotatably supported a shaft 11 which is adapted to operate a score indicia bearing dial (not shown) in a conventional and well-known manner, the said dial not being illustrated as it constitutes no part of my present invention.

Fixed to this shaft 11 is a ratchet wheel 12 carrying a stop 13 in the form of a lateral stud and adapted to bear against an adjacent portion

2

14 of a spring wire, one end 15 of which is hooked to a lever 16 and the opposite end portion coiled about the shaft 11 as at 17, with the end 18 thereof soldered or otherwise fixed to the shaft 11. The arrangement is such that as the ratchet wheel 12 is rotated, in a manner hereinafter more fully set forth, the coiled portion 17 will be placed under tension so that when the ratchet wheel 12 is released for return to its zero position, it will do so under the action of the coil portion 17. The lever 16 is pivotally connected to the mounting plate 10 through the medium of a pin 19, and one end portion of this lever 16 carries a disc 20 disposed in a notched portion 21 of a solenoid 22 of an electro-magnetic coil 23 of a well-known and approved construction, the solenoid 22 being limited in its outward movement by an adjustment screw 24. This coil 23 is mounted upon the plate 10 through the medium of a bracket 25.

20 The upper end portion of the lever 16 has pivoted thereto as at 26 a bell-crank lever 27, one end of which is angled to provide a dog 28 adapted for engagement with the teeth 29 of the ratchet wheel 12. A latch lever is indicated at 30 and includes an angled end portion providing a dog 31 adapted to have latched engagement with respect to the teeth 29 of the ratchet wheel 12. This latch lever 30 is pivotally supported from the plate 10 by means of a pin 32 and provides a tail portion 33 having a disc-shaped end portion 34 fitting into the notched portion 35 of a solenoid 36 of an electro-magnetic coil 37. This coil 37 is mounted on the plate 10 through the medium of a bracket structure 38.

25 The latch lever 30 is normally held into latched engagement with the ratchet wheel 12 by a spring 39. The dog 28 is normally held in engagement with the ratchet wheel 12 by a spring 40.

30 Mounted on the plate 10 is a bell-crank lever 41 pivotally connected to the plate by means of a pintle 42. To one of the arms 43 of this crank is attached one end portion of a spring 44, the opposite end portion of the spring being connected to the plate 10 by means of a pin 45.

35 The latch lever 30 carries a forwardly projecting finger 46 normally disposed beneath a lateral finger 47 provided by the lever 27, the arrangement being such that when the solenoid 36 is retracted, the finger 46 will engage the finger 47 to pivot the lever 27 to dispose the dog 28 from engagement with the ratchet wheel 12.

40 The arm 48 of the lever 41 has a lateral finger 49. Normally, when the dogs 28 and 31 are in engagement with the teeth 29 of the ratchet wheel 12, the finger 46 will engage an adjacent wall 50

of the finger 49 and hold the lever 41 pivoted in a cross-wise direction against the action of the spring 44 to dispose the wall 50 thereof from beneath the finger 46, permitting both dogs 28 and 31 to move into engagement with the ratchet wheel 12.

From this description, it will be apparent that both dogs 28 and 31 will remain in unlatched position by action of the lever 41 until the coil 23 is energized to pivot the lever 16. By such a construction, the ratchet wheel 12 cannot be stepped up at the completion of an operation until it has returned to zero position.

In conjunction with Fig. 1, I have illustrated a suggested circuit for the coils 23 and 37. In this connection, the circuit to the coil 23 is controlled by a bumper switch 51 of the type shown in the aforesaid patent, whereas the coil 37 is controlled by a switch 52 normally closed by a coin slide 53.

In operating the device in accordance with this circuit, in which circuit the source of electric energy is indicated at 54, when the switch 52 is closed to condition the game apparatus for play, the dogs 28 and 31 will be latched by the wall 50 of the finger 49 from engagement with the ratchet wheel 12, permitting the ratchet wheel 12 to return to zero or initial position by action of this coil spring 17. However, upon closing of the switch 51 by the engagement of a rolling ball with respect thereto, the coil 23 becomes energized, pivots the lever 16 to disengage the wall 50 of the finger 49 from the finger 46, permitting the dogs 28 and 31 to return to engagement with the teeth 29 of the ratchet wheel 12.

While I have illustrated and described the preferred form of construction for carrying my invention into effect, this is capable of variation and modifications without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A step-up mechanism in which there is a spring rotated ratchet wheel, a step-up lever, a latch lever and electro-magnetic means for operating said levers, a device for releasably latching said step-up lever and latch in an inoperative position with respect to the wheel, comprising a pivoted lever having a portion thereof adapted to engage beneath a portion of the latching lever and another portion adapted to be engaged by a portion of the step-up lever, means for

supporting said lever for said pivotal movement, and spring means for pivoting said lever in a direction to dispose the first named portion thereof in latched position with respect to the latch lever, said latch lever having a portion adapted to engage a portion of said step-up lever to latch said step-up lever from engagement with the wheel when said first named portion of said member is disposed in latched position beneath the portion of said latch lever.

2. A step-up mechanism in which there is a spring-rotated ratchet wheel, a step-up lever, a latch lever and electro-magnetic means for operating said levers, a device for releasably latching said latch lever from engagement with said wheel comprising means adapted to be engaged by a portion of the step-up lever and to be thereby pivoted from engagement with said latch lever.

3. A step-up mechanism in which there is a spring-rotated ratchet wheel, a step-up lever, a latch lever and electro-magnetic means for operating said levers, a device for releasably latching said latch lever from engagement with said wheel comprising means adapted to be engaged by a portion of said step-up lever and to be thereby pivoted from engagement with said latch lever, and spring means for pivoting said device in a direction for latched engagement with said latch lever.

4. A mechanism for releasably latching a step-up lever and a latch lever of a ratchet wheel in which the latch lever and step-up lever have interconnecting parts whereby upon movement of said latch lever said step-up lever will be releasably held from engagement with said wheel, comprising a mounting plate on which said step-up lever and said latch lever are pivotally supported, a bell-crank pivotally carried by said mounting plate and having a finger adapted to engage beneath a finger of said latch lever and adapted to be engaged by said step-up lever and be pivoted by the latter from latched engagement with said finger of the latch lever, means for pivoting said bell-crank in one direction, said bell-crank having a wall portion adapted to be engaged by said finger of said latch lever, whereby to hold said bell-crank against said pivotal movement.

EDWARD H. HUGHES.
